(57) CLAIM

The ornamental design for a display screen with an icon as shown and described.

DESCRIPTION

FIG. 1 is a front view of a display screen with an icon showing a first image in a sequence of the claimed design; FIG. 2 is a second image thereof; FIG. 3 is a third image thereof; FIG. 4 is a fourth image thereof; FIG. 5 is a fifth image thereof; FIG. 6 is a sixth image thereof; FIG. 7 is a seventh image thereof; FIG. 8 is an eighth image thereof; FIG. 9 is a ninth image thereof; FIG. 10 is a tenth image thereof; FIG. 11 is an eleventh image thereof; FIG. 12 is a twelfth image thereof; FIG. 13 is a thirteenth image thereof; FIG. 14 is a fourteenth image thereof; FIG. 15 is a fifteenth image thereof; and, FIG. 16 is a sixteenth image thereof.

The outermost broken lines in the figures show a display screen or portion thereof and forms no part of the claimed design; the other broken lines in the figures show portions of the icon that form no part of the claimed design and are provided for illustrative purposes only.

1 Claim, 16 Drawing Sheets
